Patented Nov. 28, 1922.

UNITED STATES PATENT OFFICE.

LEE TROWER, OF WILKINSBURG, PENNSYLVANIA.

SAFETY DEVICE FOR STEAM SHOVELS.

Application filed January 21, 1922. Serial No. 530,889.

To all whom it may concern:

Be it known that I, LEE TROWER, a citizen of the United States, and resident of Wilkinsburg, in the county of Allegheny and 5 State of Pennsylvania, have invented a new and useful Improvement in Safety Devices for Steam Shovels; and I do hereby declare the following to be a full, clear, and exact description thereof.

10 My invention relates to a safety-device for steam-shovels or other machines where a device of this character may be employed to equal advantage.

In the operation of steam-shovels great 15 danger to the shovel-operator and craneman is always present, due to the liability of the breaking of the hoisting-chain, which, in the operation of the shovel, is driven at a high rate of speed, and if it parts at any 20 point the chain is thrown back toward the platform on which the shovel-operator and craneman stand with great velocity, and only recently applicant has had personal experience with a case where a craneman's 25 skill was fractured and other injuries received, due to the breaking of the hoisting-chain.

The object of my invention therefore is to 30 provide means for protecting the shovel-operator and craneman from danger due to the breaking of the hoisting-chain, and to accomplish this by a device which may be applied to steam-shovels already in use, and which does not in any way interfere with 35 the operation of same.

In the accompanying drawing Fig. 1 is a 40 vertical side elevation of a portion of a common form of a steam-shovel showing my invention applied thereto; Fig. 2 is an enlarged detail of one end of the hoisting-chain guard; Fig. 3 is an enlarged section on the line 3—3, Fig. 1; and Fig. 4 is an enlarged section on the line 4—4, Fig. 1.

In the drawing the numeral 2 indicates a 45 portion of a customary car or truck on which the steam-shovel, engine and other parts are mounted.

The ordinary boom 3 has the housings 4 and 5 at its outer and inner end, respectively, 50 said housings forming the supports for the sheaves 6 and 7 over which the hoisting-chain 8 passes. This hoisting-chain passes

around the pulley 9 in the pulley-block 10, and over the sheave 11 at the extreme outer end of the boom 3 and is connected at its 55 free end to said pulley-block 10 from which connection is made to the shovel 12 in the ordinary way.

The shovel-beam 13 is connected to the shovel 12 and passes between the boom 3, 60 but as this forms no part of my invention it has not been deemed necessary to illustrate the same other than diagrammatically.

The chain-guard 14 may be of any suitable construction, that shown consisting of a tube 65 of proper diameter flattened at opposite points, as at 15, said tube being supported by the frames 16 connected to the housings 4 and 5, said frames being made up of suitable angle-irons riveted together. The guard 70 14 is cut away as at 17 at each end, said cut-away portion coming over the sheaves 6 and 7 so as not to interfere with the operation of said sheaves.

As stated above, the guard may be of any 75 construction which will prevent the chain from flying back in case it breaks, and said guard might consist of a skeleton frame made up of angles or other shapes riveted together.

In case the hoisting-chain in operation 80 should break between the sheaves 6 and 7 it will be apparent that the chain will be held confined by the guard 14 so that it cannot fly back toward the operator or crane-man on the car 2.

A vertical guard 18 is mounted on the car 90 below the sheave 7 so that the chain cannot fly back between the sheave 7 and the floor of the car. In this manner a guard is provided for the entire length of the chain between the sheave 6 and the platform, and there is no possibility in case the chain should break of its being able to reach the shovel-operator or craneman, so that fatal or 95 serious accidents are eliminated.

What I claim is:

1. In a steam-shovel, the combination with the boom, the sheaves at or adjacent the ends thereof, and the hoisting chain passing over 100 said sheaves, of a guard on the chain extending from one sheave to the other.

2. In a steam-shovel, the combination with the boom, the sheaves at or adjacent the ends

thereof and the hoisting chain passing over said sheaves, of a tubular guard extending from one sheave to the other.

3. In a steam-shovel, the combination with the boom, the sheaves at or adjacent the ends thereof, and the hoisting-chain passing over said sheaves, of a tubular guard surrounding said chain and extending from one

sheave to the other, and cut-away portions at the ends of said guard over said sheaves. 10

In testimony whereof I, the said LEE TROWER, have hereunto set my hand.

LEE TROWER.

Witnesses:

HENRY HOLZ,
JOHN F. WILL.
